UNITED STATES PATENT OFFICE

GEORGE B. HEATHER, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed February 20, 1930. Serial No. 429,946.

This invention relates to button loops particularly adapted for use in garment straps, the loop being specially adapted to be suspended at the end of a strap loop in readiness 5 to be clipped over a button the shank of which may be urged from a button-receiving loop into a smaller retaining loop from which it cannot be unintentionally withdrawn.

The objects of the invention are to provide, 10 by bending a piece of resilient wire, a reversible button loop of which the wire ends are overlapped and provided, independently of an enclosing clip member, with an interlocking means limiting the relative outward 15 movement of the overlapped ends in the plane of the loop; and to provide such a button loop with means for securing the overlapped ends against relative movement out of the plane of the loop. With these and other ob- 20 jects in view, as may become apparent from the within disclosures, the invention consists not only of the particular form herein pointed out and illustrated in the drawings but readily admits of certain modifications with- 25 in the scope of what hereinafter may be claimed.

The character of the invention may be best understood by reference to one illustrative device embodying the invention and illus- 30 trated by the accompanying drawings in which the Figure 1 is an upright elevation of the device in normal condition, a reversed elevation of which would be identical therewith; the Figure 2 is a side elevation of the 35 device; the Figure 3 is an upright elevation of the device in expanded condition.

The device is preferably made from a piece of resilient wire of which a middle portion is bent to provide the suspension loop 1 and the 40 spring arms 2 and 3 depending therefrom to provide the associated loops 4 and 5 in axial alignment and having an intermediate normally contracted throat 6. The wire end portions 7 and 8 are relatively overlapped and 45 the interfacing surfaces of the overlapped portions are provided with depressions 9 that reduce a section of each end portion 7 and 8 and provide each with a shoulder 10 adjacent the wire extremity, as illustrated by the 50 Figure 1. The shank S of a button within

the loop 4, as illustrated by the Figure 1, may be manually urged into the throat 6 by expanding the button loop as illustrated by the Figure 3, the expanding of the loop causing the overlapped end portions 7 and 8 to relatively slide along the plane of the loop, the expansion of the loop being limited by the interlocking engagement of the shoulders 10, as illustrated by the Figure 3. The clip member 11 encloses the overlapped end portions 55 7 and 8 and secures them against relative movement out of the plane of the loop.

The button loop being reversible is adapted to be mounted upon a strap to prominently display the front elevation thereof, as illus- 60 trated, or an opposite elevation not illustrated by reason of the fact that both elevations are identical.

I claim:—

1. A button loop comprising spring arms 70 cooperating to form associated loops in axial alignment and having an intermediate normally contracted throat portion, the ends of the arms overlapping and the facing surfaces of said ends having depressions providing interlocking shoulders adjacent the wire extremities, the engaging shoulders limiting the relative sliding movement of the end portions in the plane of the loops upon the expansion of the contracted throat; 75

2. A reversible button loop comprising a piece of resilient wire of which a middle portion is bent to form a suspension loop, the remaining portions cooperating to form associated loops in axial alignment and having an intermediate normally contracted throat portion, the wire end portions overlapping and the wire extremities being provided with interlocking shoulders to limit the overlapped portions in their relative sliding movement 80 upon the expansion of the contracted throat portion, and a clip securing the overlapped portions against relative movement out of the plane of the loop; 90

3. A button loop comprising spring arms 95 cooperating to form associated loops in axial alignment and having an intermediate normally contracted throat, the ends of the arms being separate and unconnected to each other, but relatively overlapped and having their 100

free extremities provided with interlocking shoulders limiting their relative movements to the plane of the loops upon the expansion of the contracted throat.

- 5 4. A wire button loop comprising spring arms cooperating to form associated loops in axial alignment and having an intermediate normally contracted throat portion, the ends of the arms overlapping and the facing surfaces of said ends having depressions providing interlocking shoulders adjacent the wire extremities, the engaging shoulders limiting the relative sliding movement of the end portions in the plane of the loops upon 10 the expansion of the contracted throat portion, and a clip securing the overlapped portions against relative movement out of said plane.

GEORGE B. HEATHER.
